UNITED STATES PATENT OFFICE.

CHARLES LOUIS BAILEY, OF GLEN RIDGE, NEW JERSEY.

THREAD-GAGE.

1,138,438.

Specification of Letters Patent.

Patented May 4, 1915.

Application filed March 17, 1914. Serial No. 825,372.

To all whom it may concern:

Be it known that I, CHARLES LOUIS BAILEY, a citizen of the United States, and a resident of Glen Ridge, in the county of 5 Essex and State of New Jersey, have invented a new and Improved Thread-Gage, of which the following is a full, clear, and exact description.

The invention relates to measuring instruments, and its object is to provide a new and improved thread gage more especially designed for use by machinists and other mechanics and arranged to enable the user to quickly and accurately determine whether 10 the thread of a screw, bolt, tap or similar threaded article, is of the correct size or not.

In order to accomplish the desired result use is made of gage members having V-shaped edges spaced apart and between 20 which a screw or other threaded article to be gaged is passed to determine whether the threaded article is of the correct size or not.

A practical embodiment of the invention is represented in the accompanying drawings forming a part of this specification, in which similar characters of reference indicate corresponding parts in all the views.

Figure 1 is a side elevation of the improved thread gage; Fig. 2 is a plan view 30 of the same with a screw to be gaged in position in the gage; Fig. 3 is a sectional plan view of the thread gage on the line 3—3 of Fig. 1; Fig. 4 is a sectional side elevation of part of the thread gage on the line 4—4 of Fig. 2; Fig. 5 is a cross section of the 35 thread gage on the line 5—5 of Fig. 1; Fig. 6 is a perspective view of the body of the thread gage; and Fig. 7 is a side elevation of a modified form of the thread gage.

The body or stock A of the thread gage is U-shaped in its upper portion, and is provided at the members of the said upper portion with recesses or guideways A', A² in which fit gage members B and C spaced 40 apart in the opening of the stock A for the passage of a screw, bolt, tap or similar threaded article D to be gaged. The gage member B is formed of two superimposed plates B' and B² each provided with V-shaped edges to form between the said edges a V-shaped groove corresponding to the V-shaped thread of the article D to be gaged, as plainly indicated in Fig. 2. The gage member B is secured in place in the recess 45 A' by screws E which also pass through a cap plate A³ held on the stock and covering the

front faces of the gage members B and C. The gage member C is formed of two plates C' and C² located one above the other and having V-shaped edges disposed directly 60 opposite the V-shaped groove formed by the plates B', B² of the gage member B. The V-shaped edges of the plates C', C² are adapted to pass between adjacent threads of the article D, as plainly indicated in Fig. 2. 65 The lower plate C² is set slightly farther inward than the upper plate C' so that the article D when of correct size can be passed downward between the upper portion of the gage member B and the plate C', but 70 is stopped from moving farther downward by the plate C² set farther inward than the plate C'. Thus the user of the thread gage can readily determine whether the article is 75 of correct size or not, for if the article passes all the way through the gage members B and C then the diameter of the article is smaller than intended. The plates C' and C² are provided with slots C³, C⁴ (see Fig. 4) through which extend screws F, F' also 80 passing through the cap plate A³ to hold the plates C', C² securely in place in the recess A².

In order to properly adjust the plates C', C² use is made of set screws G screwing in 85 the side of the cap plate A³ adjacent the recess A², the inner ends of said set screws abutting against the outer ends of the plates C', C². Thus when the screws F, F' are loosened the plates C', C² can be adjusted to 90 gage articles of a predetermined size. In practice, about four gages will be necessary for gaging threaded articles such as mentioned, from eight to forty threads per inch. One gage will be arranged to accommodate 95 threaded articles from 8 to 13 threads to the inch, another from, say, 14 to 20 threads; another from 22 to 30 threads, and another from 32 to 40 threads to the inch.

In the modified form shown in Fig. 7, the 100 cap plate A³ is dispensed with, and the sides of the body A are provided with abutment plates A⁴, A⁵, of which the abutment plate A⁵ forms an abutment for the gage member B while the abutment member A⁴ carries the set screws G. As shown in the drawings, the cap plate A³ is preferably fastened in place on the body A by a screw H and a dowel pin I to permit convenient removal 105 of the cap plate A³ for changing the gage members B and C whenever it is 110 desired to do so. It is further understood

that the same body A can be used for the different sets of gage members B and C above mentioned and be used to accommodate articles having different threads.

5 Having thus described my invention, I claim as new and desire to secure by Letters Patent:

1. A thread gage provided with oppositely-disposed gage members spaced apart 10 to form a passage for a threaded article to be gaged, the gage members having straight edges, of which one is grooved for the passage of a thread of the article and the other edge is adapted to pass between adjacent 15 threads of the article and is provided with an upper and a lower portion, of which the lower portion is set farther inward than the upper portion.

2. A thread gage, comprising a stock, gage 20 members adjustably held on the said stock and having oppositely-disposed edges spaced apart for the passage of a threaded article, one of the edges having a groove extending lengthwise of the edge for the reception of 25 a thread and the other edge being adapted to pass between adjacent threads of the article, one of the gage members being made in parts having their edges offset one beyond the other part.

3. A thread gage, comprising a stock provided with spaced arms having guideways, gage members fitting the said guideways and having oppositely-disposed edges spaced apart for the passage of a threaded article, 35 the edge of one of the said gage members having a lengthwise-extending groove for engagement by a thread of the article, and the edge of the other gage member being adapted to pass between adjacent threads of 40 the article, the said last-named gage member being made in parts, and means for adjusting one of the parts independently of the other toward the grooved member.

4. A thread gage, comprising a stock provided with spaced arms having guideways, gage members fitting the said guideways and having oppositely-disposed edges spaced apart for the passage of a threaded article, the edge of one of the said gage members 50 having a lengthwise-extending groove for engagement by a thread of the article, and the edge of the other gage member being adapted to pass between adjacent threads of the article, the last-named gage member being made in parts each having a slot, screws passing through the slots and screwing in

the said stock to fasten the gage member parts in place, and adjusting screws screwing in the said stock against the outer ends of the said gage member parts.

5. A thread gage provided with gage members, one of said members having V-shaped edges spaced apart to form a groove and between which the thread of the article to be gaged is passed, one of the members having an upper part and a lower part, of which the edge of the lower part projects beyond the edge of the upper part.

6. A thread gage provided with gage members spaced apart for the passage of the 70 article to be gaged, one of the said gage members being formed of two plates each having a V-shaped edge to form a V-shaped groove between them, and rigidly held together, the other gage member having a 75 V-shaped edge disposed opposite the said groove.

7. A thread gage provided with gage members spaced apart for the passage of the article to be gaged, one of the said gage 80 members being formed of two plates each having a V-shaped edge to form a V-shaped groove between them, the other gage member being formed of an upper and a lower plate, the plates having V-shaped edges disposed opposite the said groove, the edge of 85 the lower plate being set in advance of the edge of the upper plate.

8. A thread gage comprising a stock provided with spaced arms having guideways, 90 gage member fitting the said guideways and having oppositely disposed edges spaced apart for the passage of a threaded article, the edge of one of the said gage members having a lengthwise extending groove for 95 engagement by a thread of the article, and the edge of the other gage member being adapted to pass between adjacent threads of the article, the last named gage member being made in parts each having a slot, and 100 screws passing through the slots and screwing into the stock to fasten the gage-member parts in place and permit the edges of the parts being adjusted relatively to each other.

105 In testimony whereof I have signed my name to this specification in the presence of two subscribing witnesses.

CHARLES LOUIS BAILEY.
